OXYGEN DEMAND BREATHING SYSTEM, INCLUDING MEANS FOR AUTOMATIC ALTITUDE REGULATION

Henry Seeler, Heidelberg, Germany

Application September 21, 1948, Serial No. 50,343

3 Claims. (Cl. 128—142)

(Granted under the act of March 3, 1883, as amended April 30, 1928; 370 O. G. 757)

1

The invention described herein may be manufactured and used by or for the Government for governmental purposes without payment to me of any royalty thereon.

The present invention relates to an oxygen demand breathing system including means for automatic altitude regulation.

The primary object of the invention is to provide an automatic regulating apparatus, including a face mask equipped with automatic inlet and outlet valves, for supplying air and oxygen to a person at varying altitudes and including means to increase the degree of oxygen dilution as the altitude increases.

A further object of the invention is to provide a breathing apparatus including a face mask having pressure responsive inhalation and exhalation valves and having connected to the mask an automatic oxygen regulator which is in turn connected to a source of oxygen under pressure for supplying oxygen supplement to the mask upon response of the oxygen regulator.

A further object of the invention is to provide a system of oxygen regulation especially for aircraft personnel in which means are provided to make full use of the outside air as a source of oxygen and in which further means are provided to automatically supplement the air supply with pure oxygen as the altitude increases and the need for more oxygen increases.

Another object of the invention is to provide an oxygen demand system for aircraft personnel wherein the system includes one or more face masks each having an automatic air inlet valve and an automatic outlet valve and wherein an oxygen regulator connected to each face mask acts to supply pure oxygen to aircraft personnel as the demand therefor arises, as for instance with increase in altitude.

Another object of the invention is to provide an oxygen demand regulator wherein a control diaphragm subject to atmospheric pressure on one side is subject to breathing pressure on the other side and wherein the control diaphragm acts on a control valve to supply oxygen to the subject when he inhales and to cut off such oxygen when he exhales. A related object of the invention is to include in the regulator means responsive to the decreased pressures at high altitudes to increase the flow of oxygen to the subject in direct proportion to the increase in altitude.

Another object of the invention is to provide an improved system of oxygen regulation in which the supply of oxygen to the subject is pro-

portional to the current demand for the oxygen and in which the proportioning of air and oxygen is accomplished automatically.

Another object of the invention is to generally improve the reliability and efficiency of oxygen regulators for use with aircraft personnel equipped with face masks or their equivalent.

The above and other objects of the invention will become apparent upon reading the following 10 detailed description in conjunction with the drawing, in which:

The single figure of drawing shows in vertical cross section a face mask in place on a man's face and shows in adjacent relation the oxygen 15 regulator or diluter as used with the mask.

As commonly known a person can not survive at high altitudes unless the air he is breathing is enriched by the addition of oxygen. While there is no certain altitude at which the oxygen 20 supply should be augmented, in general it may be stated that additional oxygen should be used above 12,000 feet reckoned from sea level and must be used above 15,000 feet if consciousness is to be maintained. While it is possible to substitute oxygen for air at higher altitudes, it is preferable to dilute the rarefied air with pure oxygen so that the proportion of oxygen in the 25 gaseous mixture is increased as the altitude increases. Thus the present system utilizes an 30 automatic oxygen regulator which may also be called a diluter. This part of the system is connected to the face mask by two thin tubes.

Mask construction

35 For a description of the breathing apparatus reference is made to the drawing. The subject 1 is shown wearing a mask 2 which covers the nose and mouth and which may be held in place by straps secured behind the subject's head. At 40 the lower side of the mask there is a pressure relief valve or outlet valve 3 which includes a housing 4 enclosing a disk valve 5 and coil spring 6. The disk valve 5 normally seats on an annular valve seat 7 but on exhaling the pressure 45 in the mask is increased to open the valve 5 and allow escape of the exhaled air. On the forward wall of the mask there is provided a suction valve or inlet valve 8, which includes a flapper element 9 of soft rubber held in place by radial arms 10 secured to the mask wall as shown. Inside the mask wall there is a valve seat 11 against which the marginal edges of the flapper element 55 may engage. Thus the valve 8 is normally closed but when the gas pressure inside the mask is negative or slightly below atmospheric, as it is

during the inhalation phase of the breathing cycle, the small difference between outside and inside pressures causes the flapper element 9 to leave the valve seat 11 and thus allow atmospheric air to enter the mask. In the drawing the inlet or inhalation valve 8 is shown in the open position and the outlet or exhalation valve 3 is in the closed position. Thus at the instant depicted the subject 1 is inhaling and is drawing air from the free atmosphere into the mask. Extending away from the mask are two thin flexible tubes 12 and 13 having open end portions terminating inside the mask. These tubes, known as the oxygen tube and the control tube respectively, extend some distance to the automatic regulator or diluter 14.

Instead of the flapper-type of inlet valve made of rubber or other flexible material it may be preferred in some instances to use other forms of sensitive valve devices, such as the disk-and-spring type of valve like the outlet valve 3. Since the gas pressures inside the mask are preferably kept rather low, the outlet and inlet valves are made to respond to very small pressure differentials accordingly, and must be carefully calibrated and tested for accuracy of response. In the present system an example of the critical pressures for the valves may be stated as twenty millimeters of water for the outlet valve and five millimeters of water for the inlet valve. In some cases these values may be changed considerably but it must be understood that the pressure as stated for the outlet valve refers to a pressure inside the mask above atmospheric, while the pressure as stated for the inlet valve refers to a pressure inside the mask below atmospheric. Thus as the altitude is increased and the supply of oxygen to the mask is increased by the oxygen regulator, the air inlet valve 8 will respond less readily upon inhalation. The effect of the poorer response of the inlet valve will be made clear as the description of the present system proceeds.

Regulator construction

The regulator or diluter unit 14 of the present oxygen demand system includes a two-part housing comprising an upper housing part 15 and a lower housing part 16. Clamped between these parts is a very thin diaphragm 17, which may be made of a rubberized textile fabric. While the dimensions are not critical it is noted that a very satisfactory element may be produced having a thickness of about 0.015 of an inch and a diameter of about one and one-half inch. The diaphragm 17 separates the regulator housing into two parts, the upper or aneroid chamber and the lower or control chamber. In the lower part of the control chamber there is another diaphragm 18 providing therebelow a pressure chamber adapted at certain times to receive oxygen at appreciable pressures. The outer marginal edges of the diaphragm 18 are secured to the housing part 16 and the inner edges of the diaphragm are secured to the regulator member 19. This second diaphragm is thicker and less sensitive than the diaphragm 17, preferably being around 0.080 of an inch thick and also being made of a rubberized textile fabric.

Considering now the aneroid chamber it is seen that the upper housing part is provided with a boss threaded internally to adjustably receive a threaded stud 21 having an aneroid bellows 22 secured thereon within the aneroid chamber. The upper end of the stud carries a lock nut 23 to

hold the stud and attached bellows in fixed position after adjustment. The aneroid chamber is open to the atmosphere by way of small apertures 24. The aneroid bellows, which contains a compression spring, is sealed up in a vacuum. Therefore at sea level the aneroid will be compressed by the pressure of the atmosphere acting thereon, but as the altitude increases and this pressure is decreased the bellows will gradually expand thus exerting pressure on the coil spring 25 and also on the diaphragm 17. Cemented or otherwise secured to the underside of the diaphragm 17 is a pressure plate 26 adapted to bear on the free end of a lever 27, the lever being pivoted or fulcrumed on an abutment 28 secured to the housing part 16. A second lever 29 contacts the first lever 27 between its end points and is fulcrumed on an abutment 30 secured to the housing part 16. The inner end of the second lever receives the stem of a control valve or pilot valve 31 having a cone-shaped poppet element at its lower end. This poppet element, which may have a ball-like shape if desired, is operative to normally close the valve passage 32 by action of a coil spring 33 surrounding the valve stem. However when the subject inhales there will be a reduction in pressure in the mask 2, in the control tube 13 and in the control chamber below diaphragm 17 and the diaphragm will therefore bulge downwardly thus acting on levers 27 and 29 to raise the valve member 31 and open the passage 32. Around the stem of valve member 31 and also encircling an inwardly extending portion of the member 19 there is a rubber sealing band 34 to more effectively close off the interior of member 19. Forming part of the member 19 is a valve element 19' extending down into an oxygen chamber 35. A coil spring 36 surrounds the element 19' and acts to hold this element as well as the member 19 in a lower or cut-off position. A rubber sealing band located just inside the spring 36 acts in the same way as the previously described band 34 to more effectively seal the oxygen chamber 35 from the pressure chamber under diaphragm 18. The lower wall of chamber 35 is provided with an elevated valve seat 37 against which the valve element 19' closes to prevent escape of oxygen into the chamber. Through the center of valve seat 37 there extends an oxygen inlet passage 38, which opens into a tubular projection 39 adapted to be connected to a source of pure oxygen under pressure. This cup-like projection 39 is provided as a receptacle for a ceramic gas filter which acts to prevent dust and other foreign matter from reaching the delicate regulator and from reaching the face mask. It is further noted that the pressure chamber below the diaphragm 18 is open to the atmosphere by way of a narrow pinhole opening 40, while the interior of the valve member 19 is open to the pressure chamber by way of a passage 41.

The oxygen regulator for use in the present oxygen demand system or in other similar systems is more specifically disclosed and claimed in my copending application Serial No. 54,188 filed October 12, 1948, and entitled "Pressure Responsive Regulator or Relay for Use in Oxygen Demand Breathing Systems."

Operation

The present oxygen supply or regulator system is characterized by its response to the demand for oxygen as evidenced by a reduced pressure in the control chamber of the regulator or diluter.

This reduced pressure is present also in the mask and therefore the demand may effect a brief opening of the inlet valve 8 as well as effecting an influx of oxygen from the regulator. Under average conditions, that is at moderately high altitudes, the oxygen is thus used to dilute the air supply but of course its ultimate effect is to increase the proportion of oxygen in the mixture being breathed by the subject 1.

It will be assumed that the subject 1 is inhaling in the drawing illustration and is receiving air through the flapper valve 8. Also his inhalation has induced a low enough pressure in the regulator control chamber to cause the opening of the passage 32, by reason of a slight elevation of the control valve member 31. This in turn lets oxygen into the member 19 and also into the pressure chamber below diaphragm 18 causing the member 19 to be elevated and thereby permitting oxygen to flow into the chamber 35 by way of the oxygen inlet passage 38 and also into the face mask 2 by way of the supply tube 12. The operating conditions described may correspond to the action obtained at a moderate altitude of about 12,000 feet above sea level. At this time the proportions of air and pure oxygen inside the mask during inhalation will probably be in the neighborhood of one to one by volume. Now when the subject exhales the pressure inside the mask will rise abruptly, thus closing the air inlet valve 8 and simultaneously causing the outlet or exhaust valve 3 to open so that the used up air and respiration products may be expelled into the outside atmosphere. Also the increase of pressure in the mask will be transmitted along the control tube 13 to increase the pressure in the control chamber of the regulator, thus raising the diaphragm 17 and lowering the valve member 31 by action of the coil spring 33. This action in turn closes the passage 32 and cuts off the flow of oxygen to the chamber below the diaphragm 18, allowing the gas pressure therein to become equal to atmospheric by reason of the escape passage 40. Now by the action of the coil spring 36 the valve member 19 will be forced down into a position closing off the oxygen passage 38. By this automatic cut-off action the limited supply of pure oxygen in a charged container is conserved and is drawn upon only during the inhalation phases of the breathing cycles. Furthermore the exhalation effort of the subject 1 will be kept at a minimum, since the flow of oxygen to the mask is cut off as soon as exhalation commences.

Considering now the action of the oxygen demand system at a considerable altitude, for example about 22,000 feet above sea level, it is first noted that the aneroid bellows 22 will be slightly elongated compared to its length as shown in the drawing because of reduced atmospheric pressure. Now the coil spring 25 will be compressed to a greater degree than before and the resultant increased force exerted on the control diaphragm 17 and on the lever system 27, 29 actuated thereby will act to hold the control valve 31 slightly open even though the subject 1 is not inhaling nor exhaling at the moment. With the valve 31 open the pressure build-up in the pressure chamber under diaphragm 18 will act to hold the oxygen supply valve 19' off the valve seat 37 and thus allow oxygen to flow through the chamber 35 and tube 12 into the mask 2. Now when the subject inhales, the reduced pressure in the control chamber will cause the diaphragm 17 to move downwardly still farther under the force of spring

25 and atmospheric pressure acting on top of the diaphragm. The response of the levers 27 and 29 and valve 31 will cause a more definite elevation of the oxygen supply valve 19' and a consequent plentiful supply of oxygen to the mask through the tube 12. The valve 19' may have a throttling action when it is raised only slightly off the valve seat 37, so that upon further elevation of the valve there will be a maximum flow of oxygen. Although the oxygen pressure chamber is open to the atmosphere the passage 40 is of pinhole proportions, and is provided only for the purpose of allowing the pressure under the diaphragm 18 to return to atmospheric after closing of the valve 31. At the higher altitude under consideration presently the air inlet valve 8 will open during inhalation but only for a short time compared to the total time for the inhalation phase, since there is a slightly increased pressure inside the mask due to the more pronounced opening of the oxygen supply valve 19'. There will be some air admitted through the inlet valve 8 at each inhalation but there will be a greater proportion of oxygen and a smaller proportion of air under the circumstances set out. For example there may be 80 percent pure oxygen and 20 percent air inside the mask during inhalation. Thus it is seen that as the altitude is increased and the inlet valve 8 opens less, the extent of oxygen dilution of the air being breathed will be increased proportionately. As explained previously the valves 31 and 19' will close upon exhalation because of pressure developed inside the mask 2 and within the control chamber connected to the mask by the tube 13.

Operation of the regulator at extreme altitudes, for example at 35,000 feet above sea level, differs from that explained above mostly in the further elongation of the aneroid bellows 22 and the further compression of the coil spring 25. Under these conditions of reduced atmospheric pressure the force of the spring 25 is the main influence in opening the control valve 31. The lack of atmospheric pressure on the upper side of the control diaphragm 17 will mean that during inhalation the diaphragm will not have any marked tendency to bulge downwardly, as it would at lower altitudes where the atmospheric pressure is greater. The main influence in keeping the valves 31 and 19' open under these conditions will be the bellows 22 and the spring 25 and it should be noted that this will be a constant force at a constant altitude. This actuating force now being at a maximum, the assisting forces or the counter forces will not have much effect unless they are too increased in magnitude. However, since these forces developed during the breathing cycle will not increase noticeably at higher altitudes the bellows is the main factor at the extreme altitude. It will be seen that the valves 31 and 19' will now be held open at all times except during exhalation, and as a result the pressure inside the mask will tend to build very slightly from the influx of pure oxygen from the regulator 14. The subject may now inhale with less effort and the inhalation phases will not cause the air inlet valve 8 to unseat at all. Thus he will now be breathing pure oxygen at all times. As he exhales there will be an increase in gas pressure inside the mask and the outlet or exhaust valve 3 will open to release most of the expelled respiration products. The pressure increase will be transmitted to the control chamber of the regulator by means of the control tube 13 and the diaphragm 17 will bulge

upwardly. The resulting action will cause the control valve 31 to seat for a brief time and thus cause seating of the oxygen supply valve 19' at least momentarily. Thus as the demand is removed the oxygen supply is cut off and the oxygen consequently conserved for the inhalation phases of breathing. By the use of the automatic inlet and outlet valves built into the mask and also the oxygen regulator connected thereto, the present demand system operates to not only proportion the supply of pure oxygen to meet the demand but also operates to make use of the outside air as a source of oxygen. This combined action of the air valves in the mask structure and the oxygen demand regulator is the most important aspect of the present invention, but of course the automatic altitude regulation or compensation whereby the oxygen supply is increased with increase in altitude is also an important feature. Another noteworthy feature is the maintenance of positive mask pressures at higher altitudes, so that any possible leakage around the edges of the mask will merely let gases out of the mask rather than permit the thin air to seep into the mask.

In passing it is noted that there are varying pressures on the opposite sides of the diaphragm 18 but they are of such differences in magnitude that variations in pressure on the upper side of this diaphragm during the breathing cycle may be ignored entirely. The only important consideration as far as the operation of the diaphragm 18 is concerned is the rise and fall of the oxygen pressure under the diaphragm as the control valve 31 is opened and closed. While the oxygen pressure in the supply chamber 35 may often be quite considerable, the throttling effect of the oxygen supply tube 12 and the valve passage 38 always ensures that no such pressure will develop inside the mask. It must be remembered too that the mask and the subject together provide a large volume for the gas to fill and the oxygen supplied thereto must pass through a very small tube and must traverse some distance therethrough also. As the oxygen supply is used up the supply pressure is rapidly reduced, for example the initial pressure at the neck of the oxygen bottle may be as high as 400 pounds per square inch and it will continue to fulfill its function in the present system until the pressure has fallen below about 5 pounds per square inch.

It might be noted further that the control tube 13 also exerts a throttling effect on the pressures developed within the control chamber of the regulator 14 but in any case the control pressure will always be in direct proportion to the pressure inside the face mask 2. Although the system as illustrated and described includes a face mask covering both the nose and mouth, it is understood that various types of masks or appliances may be used to connect the subjects with the source of oxygen and with the outside atmosphere. The term face mask as used herein may accordingly be considered to apply to a mask as shown or to any reasonably similar equivalent thereof. It is clear also that a plurality of masks and regulators may be connected to a single source of pure oxygen but it is preferred to include a separate container of oxygen for each subject. While the regulator has been described and illustrated as though it were always maintained in a vertical position it should be understood that operation will be very satisfactory in other positions thereof.

The embodiments of the invention as herein shown and described are to be regarded as illustrative only and it is understood that the invention is susceptible to variations, modifications and changes within the scope of the appended claims.

I claim:

1. In an oxygen demand breathing system for use at varying altitudes, a face mask, an air inlet valve carried on said mask and responsive to a negative pressure inside said mask to open for admission of air into said mask, an exhalation valve carried on said mask and responsive to a positive pressure inside said mask to open for expulsion of products of respiration from said mask, conduit means to conduct oxygen from a charged container to said mask, an oxygen regulator including a housing and connected in said conduit means to regulate the amount of oxygen reaching said mask from said container, an oxygen valve in said regulator housing to allow oxygen to pass from said container to said face mask by way of said conduit means, spring means in said regulator housing to bias said oxygen valve toward closed position, a pressure sensing tube connected between said mask and said regulator housing, a flexible diaphragm in said regulator subject to atmospheric pressure on one side and to the pressure of said pressure sensing tube on the other side, means in said regulator housing including an aneroid bellows and a compression spring for exerting additional pressure on said one side of said diaphragm proportional to altitude above sea level, means in said regulator housing responsive to displacement of said diaphragm as the pressure on the other side thereof is reduced to a minimum to open said oxygen valve, and said spring means providing force to close said oxygen valve as said diaphragm is displaced by increase of the pressure on the other side thereof above said minimum.

2. In an oxygen demand breathing system for use at varying altitudes, a face mask, an air inlet valve carried on said mask and responsive to a negative pressure inside said mask to open for admission of air into said mask, an exhalation valve carried on said mask and responsive to a positive pressure inside said mask to open for expulsion of products of respiration from said mask into the atmosphere, conduit means to conduct oxygen from a charged container to said mask, an oxygen regulator including a housing and connected in said conduit means to regulate the flow of oxygen from said container to said mask, an oxygen valve in said regulator housing to allow oxygen to pass from said container to said mask by way of said conduit means, spring means in said regulator housing to bias said oxygen valve toward closed position, a pressure sensing tube connected between said mask and said regulator housing, a flexible diaphragm in said regulator subject to atmospheric pressure on one side and to the pressure of said pressure sensing tube on the other side, means in said regulator housing for exerting additional pressure on said one side of said diaphragm proportional to altitude above sea level, means in said regulator housing responsive to displacement of said diaphragm as the pressure on the other side thereof is reduced to a minimum to open said oxygen valve, and said spring means providing force to close said oxygen valve as said diaphragm is displaced by increase of the pressure on the other side thereof above said minimum.

3. In an oxygen demand breathing system for

use at varying altitudes, a face mask, an air inlet valve carried on said mask and responsive to a negative pressure inside said mask to open for admission of air into said mask, an exhalation valve carried on said mask and responsive to a positive pressure inside said mask to open for expulsion of products of respiration from said mask into the atmosphere, conduit means to conduct oxygen from a charged container to said mask, an oxygen regulator including a housing and connected in said conduit means to regulate the flow of oxygen from said container to said mask, an oxygen valve in said regulator housing to allow oxygen to pass from said container to said mask by way of said conduit means, spring means in said regulator housing to bias said oxygen valve toward closed position, a pressure sensing tube connected between said mask and said regulator, a flexible diaphragm in said regulator housing subject to atmospheric pressure on one side and to the pressure of said pressure sensing tube on the other side, an aneroid bellows in said regulator having one end adjustably mounted on a regulator housing wall which is open to the atmos-

phere, a compression spring between the other end of said bellows and said one side of said diaphragm, means in said regulator housing responsive to displacement of said diaphragm as the pressure on the other side thereof is reduced to a minimum to open said oxygen valve, and said spring means providing force to close said oxygen valve as said diaphragm is displaced by increase of the pressure on the other side thereof above said minimum.
